UNITED STATES PATENT OFFICE.

SAMUEL A. GREENLEE, OF CLARKSVILLE, PENNSYLVANIA.

FEED-DEALERS' CALCULATED PRICE-LIST.

SPECIFICATION forming part of Letters Patent No. 357,663, dated February 15, 1887.

Application filed February 12, 1886. Serial No. 191,904. (No model.)

To all whom it may concern:

Be it known that I, SAMUEL A. GREENLEE, of Clarksville, Greene county, Pennsylvania, have invented a new and useful Improvement 5 in Feed-Dealers' Calculated Price-Lists, which improvement is fully set forth in the following specification, reference being had to the accompanying drawing.

Similar letters of reference indicate corresponding parts.

This invention has relation to improvements in calculators; and it consists in the construction and arrangement of parts, as will be hereinafter described, and particularly pointed out 15 in the claims.

The object of my invention is to provide a suitable device known as a "price-list" for mill-men or feed-dealers, whereby the price of grain, &c., is always calculated, as will be seen 20 in the accompanying drawing, in which the figure illustrates a perspective view of my device, a part of the top boxing being broken away to show the means for carrying the movable slotted arm, all of which will be more fully hereinafter specified.

The letter A designates the frame of my improvement, made in rectangular form, having at its top portion a cap or boxing, A', for a purpose hereinafter described. To the face 30 part of this frame is secured a card-board, A''. At the top of said board, in a horizontal line, is a row of figures ranging from 60c. to \$2.25. These figures represent the price per hundred-weight. Immediately under each of the "hundred-weight figures," so called, is a vertical double companion row of figures. These two vertical rows lie parallel and are ruled into equal squares. The left vertical row represents the number of pounds from 1 to 12 and from 35 90 to 99, and its parallel companion row indicates the price in cents from 1 to 7 and 54 to 59. In practice the left vertical row of figures, indicating pounds, is from 1 to 99, inclusive, and its companion row of calculated figures, 40 representing cents, ranges from 1 to 59. The break in the consecutiveness of the figures in the vertical lines, as shown in the drawing, is made to condense and simplify the illustration. A similar omission is made in the horizontal 45 line of figures representing the price per hundred-weight. In practice this horizontal line

increases from left to right and decreases from right to left in its price representation by an arithmetical ratio of five cents. No increase or decrease in price less than five cents per hundred-weight or multiples thereof is estimated in the calculation.

As it would not be practical to make all possible calculations between the minimum price aforesaid and the maximum, and also 60 for every pound from one up to ninety-nine pounds, I present what I deem proper to fully show my invention.

The letter B indicates a slide movable horizontally. This slide has a central vertical slot 65 corresponding in width to the width of two of the vertical rows of figures. The letters *a a* indicate the two parallel vertical arms of the slide. The lower end of said slide is provided with a handle, B'.

The upper end of the slide or movable arm B is provided with two short bent arms, *b b*, in which are journaled two rollers, *c c*. These rollers are mounted on a cross-bar, D. The ends of this cross-bar are secured at *e* to the 75 inner ends of the boxing A'. This bar is shown through the broken opening in the boxing. The continuation—outer ends thereof—is shown in dotted lines.

The operation of the device is as follows: 80 When the value of feed is seventy-five cents per hundred-weight, the slide B is moved so that the "75c. per cwt." on the board will appear through the slot in the side—*i. e.*, between the arms *aa* of said slide. When in this position, the double vertical row of figures—one indicating pounds from 1 to 99 and the other cents from 1 to 74—also appears through said slot. Now, these two companion parallel vertical lines are so arranged that immediately adjoining on the right each figure representing pounds is the figure which indicates the price at 85 seventy-five cents per hundred-weight. Suppose ninety-five pounds of feed are sold at seventy-five cents per hundred-weight, (the slide 90 being in the position shown in the accompanying drawing.) It will be seen by referring to the figure 95 in the vertical "lbs." line that the figure 71 appears as its companion. It thereby readily appears that at seventy-five cents per 95 hundred-weight ninety-five pounds will cost 100 seventy-one cents. At the same price per hun-

dred-weight ten pounds will cost eight cents, ninety-eight will cost seventy-four cents, &c.

All calculations, of course, are previously made and printed, so that the price per hundred-weight and the figures and cents in the vertical companion lines will correspond and readily disclose the desired information, substantially as set forth in the illustration and description given above of the rate at seventy-five cents per hundred-weight.

In the drawing it will be seen that a thin vertical line separates the double companion rows representing "lbs." and "cts." while a comparatively heavy line (and in practice preferably a colored one) separates the double companion rows. By this means the eye can readily follow a line and locate the desired figures without the aid of the movable handle or slotted slide. The slide, however, is so easily manipulated that it is preferably employed in locating the right figures.

Having thus described my invention, I claim as new and desire to secure by Letters Patent—

1. A board having on its face a horizontal row of figures, preferably at its top, representing a price per hundred-weight, a series of figures in double companion rows running at right angles to the said hundred-weight row, each of the double companion rows representing pounds and cents, respectively, and lying immediately under the figure in the hundred-

weight row with which it conforms, in combination with a vertically-slotted slide movable horizontally, the slot in the said slide conforming in width to the width of one of the double companion rows representing pounds and cents, substantially as described, and for the purposes set forth. 35

2. A board having on its face a horizontal row of figures, preferably at its top, representing a price per hundred-weight, a series of figures in double companion rows running at right angles to the said hundred-weight row, each of the double companion rows representing pounds and cents, respectively, and lying 40 immediately under the figure in the hundred-weight row with which it conforms, in combination with a vertically-slotted slide movable horizontally, the slot in said slide conforming in width to the width of one of the double 45 companion rows representing pounds and cents, and a boxing or cap at the top of the board, substantially as described, and for the purposes set forth.

In testimony that I claim the foregoing as 55 my invention I hereto set my hand in presence of two witnesses.

SAMUEL A. GREENLEE.
